UNITED STATES PATENT OFFICE.

DOZIER FINLEY, OF BERKELEY, CALIFORNIA, ASSIGNOR TO THE PARAFFINE COMPANIES, INC., OF SAN FRANCISCO, CALIFORNIA, A CORPORATION OF DELAWARE.

STRIP SHINGLE.

Application filed October 4, 1924. Serial No. 741,667.

My invention relates to shingle-simulating roofing elements, and one of the objects of the invention is the provision of a roofing element all of the units of which are identical in shape and which may be cut substantially without waste from the parent sheet.

Another object of the invention is the provision of a roofing element, the units of which can be laid together to simulate shingles and with a minimum of effort.

Another object of the invention is the provision of a roofing element adapted to be cut from a parent sheet and which will cover more surface when laid than is occupied in the parent sheet.

Other objects of the invention together with the foregoing will be set forth in the following description of the preferred embodiment of means which is illustrated in the drawings accompanying and forming part of the specification.

It is to be understood that I do not limit myself to the showing made by the said description and drawings as I may adopt variations of my preferred form within the scope of my invention as set forth in the claims.

Referring to the drawings:

Figure 1 is a plan view of a strip of roofing material cut into roofing elements. The transverse dash and dot line 2-2 marks the progress of the cutting operation, that portion of the strip to the left of the line having been completely cut or formed into roofing elements and that portion to the right of the line remaining to be cut. In this latter portion the lines of severance are indicated in dotted lines. The arrow 3 indicates the direction of movement of the strip thru the cutting mechanism.

Figure 2 is a plan view, on a somewhat larger scale than Figure 1, of one of the roofing elements. All of these elements cut from the parent sheet are exactly alike.

Figure 3 is a plan view of two roofing elements or units as laid together in the same course. The dotted lines indicate the units of the next lower course.

Figure 4 is a plan view of a portion of roof covered with my roofing element.

Figure 5 is a detail on a larger scale showing that portion of the transverse cut between two elements enclosed in dotted lines in Figure 1.

The material from which I preferably

form the roofing element of my invention consists of a felt-like base which is saturated with a bituminous saturant of semi-solid character at the ordinary temperature of the atmosphere, and which is coated on one or both sides with a harder bituminous compound, into which, on one side, are embedded granules of crushed slate, serpentine or like material of a size approximating that of a grain of wheat, in other words the so-called slate surfaced roofing of commerce. At the present time I prefer to cut my roofing elements on a machine such as that illustrated in the Rosener application, Serial No. 627,496 filed March 24th, 1924, and which is characterized by the fact that the severing cuts are advanced along the sheet or strip of roofing in a line perpendicular to the longitudinal axis of the strip, so that as the strip advances thru the cutting machine there is always a line perpendicular to the longitudinal axis of the strip which separates the strip which has been cut from the strip which is about to be cut. Such a line is that designated by the reference characters 2-2 in Figure 1.

In order to make the roofing element of my invention and the method of its cutting clear, it will be first discussed with reference to that portion of Figure 1 lying to the left of the line 2-2, that is, with reference to a parent strip of roofing which has been severed into the individual units or roofing elements, or shingle strips, but with said elements still lying together in what will be referred to in this description as the "cutting position" to differentiate from the "laying position" which the elements will occupy when laid in a roof.

In the cutting of the roofing elements the parent strip is divided by three longitudinally extending parallel cuts 12, 13 and 14 into four narrower strips which are divided by the transversely extending cuts designated as a whole in Figure 1 by the reference characters 16 and 17, into alternately occurring groups of four individual units or roofing elements, the first group composed of units 18, 19, 21 and 21 and the second group composed of units 22, 23, 24 and 25. When the roofing elements or units are laid in a roof, it is desired, if the unit be a long one such as that shown in Figure 1 and Figure 2, to form the exposed portion of the unit with slots so as to provide in each

unit, shingle-simulating tabs, the slots appearing to be, in the laid roof, the spaces between the individual shingles. These slots are cut in the elements at the same time the elements are separated from the parent sheet, thus in the units 18 and 19, slots 27, 28 and 29 are formed, half in each unit. These slots may all be of the same width or they may vary somewhat in width for the sake of destroying the tendency to geometrical regularity in the laid roof. While this factor is of little importance structurally, it is of very real importance artistically and commercially. In a similar manner slots 31, 32 and 33 are cut in the two elements 20 and 21; and slots 34, 35 and 36, in the elements 23 and 24 of the next group, are formed in the same manner. In this group however the outside elements 22 and 25 are formed with slots 37, 38 and 39, and 41, 42 and 43 respectively in their outer edges.

While at first glance the severing cuts 16 and 17 appear to be of different character and the units of the two groups appear to be of different shapes, such units are, in fact, identical in shape, that is to say, they are congruent figures in plan. This congruency at once becomes obvious if each of the elements 19 and 22 for example, is reversed about an axis perpendicular thereto, when it will be observed that they may each be superposed upon the element 18 with complete coincidence of outline. It will also be observed that each unit in cutting position, that is, as illustrated in Figure 1, is completely complementary to the next succeeding unit at either end from which it is separated by a single severing cut; and it is to be further observed that whether we regard the severing cut at one end of the unit, or the cut at the other end of the unit, each is defined by a line in reverse symmetry about a point between the longitudinal edges of the elements, and in the pattern illustrated in Figure 1, lying on the broken lines defining the cuts. As a result of this reverse symmetry, the edges, which are completely complementary in the cutting position, form homologous sides in the several units which exactly coincide when one unit is superposed upon another in laying position, that is, in the position of the units 18, 20, 23 and 25 of Figure 1, or of the unit shown in Figure 2.

Considering now the separate unit or roofing element shown in Figure 2; the right hand edge is defined by a broken line best shown in Figure 5, and comprising the portions 46, 47, 48, 49 and 51 and this line is in reversed symmetry about a point 52 in the center of the portion 48. Considering now the left hand transverse edge; it is found to be defined by a broken line best shown in Figure 5, and comprising the por-

tions 53, 54, 55, 56, 57, 58 and 59 which are in reversed symmetry about the point 61 which lies midway in the portion 56.

In each of the transverse edges of the roofing element a projection is formed. If 70 the line portion 51, Figure 5, be taken as the base, there is formed a projection 62, between the lines 48 and 49, and a projection 63, bounded on the outer edge by the line 46. On the opposite end, regarding the line 75 portion 49 as a base, a projection 64 is formed between the lines 56, 57 and 58, and also a projection 66 bounded on the outer edge by the line 53. When the roofing elements are placed end to end in their laying 80 position in a course, projections 63 and 66 abut, and also projections 62 and 64, as shown in Figure 3. These edges also are complementary in their laying position, to the extent that actual contact takes place. 85

Because of the abutting projections on the adjacent ends of the elements, the edges 51 and 59 are spaced apart a distance preferably equal to one of the slots such as the slot 29, so that in the laid roof the slot 67 90 thus formed between adjacent elements in the same course, are not distinguishable from the other slots formed in the edge of each element. The lower pair of abutting projections 62 and 64, close the upper end of the 95 slot 67 so that rain driving into the slot is retarded from further progress. Some water however may be driven thru the crack between the abutting projections no matter how tightly the shingle elements may be 100 laid. Of course too, capillary action will draw moisture thru this crack, but the capillary attraction is destroyed by the opening or gap 68, formed by the union of the recesses between the projections, and such 105 moisture drains backwardly under the edges of the adjacent shingles into the slot 67 or out from under the lower edge of the adjacent shingle tabs.

The extent of exposure to the weather of 110 such a roofing element as I have illustrated in Figure 2 is normally determined by and made equal to the length of the slots 27, 28, and 29, the length being the distance measured inwardly from the lower edge of the 115 element. It is evident that in laying any number of such elements shingle-fashion, the overlap of the first and third elements, counting up or down the slope of the roof, will be the width of an element minus the 120 sum of the lengths of two slots. If then, the length of the slot 67 in Figure 3 is equal to the length of the slots 28, 29, 39 and 38, the line 47—54, Figure 3, which bounds the upper portion of the gap or recess 68 125 will fall in coincidence with the upper edge of the roofing element lying next below. However in practice I prefer to make the slot 67 longer than the slots 28, 29, 39 and 38 by an appreciable amount, whereby the 130

- line 47—54 is brought nearer to the longitudinal axis 71 of the roofing element by an exactly equal amount, and thereby a certain amount of roofing material above the line 5 47—54 is brought into overlapping relation to the uppermost part of the roofing element lying next underneath, as shown in Figure 3. By this means the waterproofness or 10 tightness of the assembly at the end junction of the roofing elements is notably improved. In practice I find that making the slot 67 one quarter of an inch longer than the adjoining slots, will satisfactorily accomplish the purpose just described.
- 15 It should be noted in passing that the right hand end of the roofing shingle shown in Figure 2 may be defined by a line, the portions 51 and 46 of which lie in the same straight line, in which case the projection 20 63 is reduced to zero value. Such a change would of course be compensated by a corresponding increase in the length of the projection 66. The quality of reversed symmetry about the points 52 and 61 is however 25 not affected.
- It is evident that the roofing unit, as shown in Figure 2, is longer on the top edge 72 than on the bottom edge 73. In the manner in which the roofing elements are cut from 30 the sheet as illustrated in Figure 1, an average linear amount of material is required per element, equal to the sum of the lengths of the top and bottom edges divided by two. In all other methods of cutting identical 35 roofing elements of which I am aware, the linear amount of material required is equivalent to the length of the longer edge. In other words the method of cutting which I have set forth in the foregoing description results in a saving, per element, of an 40 amount of the parent sheet or strip represented by one-half the difference between the length of the top and bottom edges, multiplied by the width of the element itself.
- 45 As these elements are $3\frac{1}{4}$ inches long on the edge 72 and $3\frac{3}{4}$ inches long on the edge 73, and $9\frac{3}{8}$ inches wide, it is evident that for each element, $2\frac{1}{2}$ square inches are saved from waste by my method of cutting. 50 This amounts to about $\frac{8}{10}$ of 1%, which in the large volume of such roofing elements manufactured and sold, is no insignificant amount.
- A further advantage will be found in 55 these roofing elements when the question of placing and securing them on the roof is considered. In laying such roofing elements the workman usually works from left to right. Referring to Figure 3, after the fastening of element 18 by the nails 76, the element 22 would be placed and secured. This is done by first placing the shingle strip in the position shown and then gauging the right hand end by means of a shingler's 60 gauge affixed to the nailing hatchet, or it is 65 gauged by positioning the lower edge of the element with relation to the top of the slots in the element lying immediately below. The outer end is then secured in place by a single nail, the workman being assured while 70 fastening the right hand end that the left end has been held in place by the interlocking of the projections 64 and 62. If it were not for the interlocking relationship of these 75 projections, the element 22 would tend at this time to slip downroof at its left end, requiring the use of the hand to hold that end in place or approximately in place while at the same time securing the opposite or right end. After the first nail is driven into 80 the right hand end, the other nails are driven and the next shingle in the course laid and secured in the same manner.
- Another advantage of my method of cutting, lies in the fact that the area covered by the two elements 18 and 22 in the cutting position as shown in Figure 1 is less than the area covered by these same two elements in 85 the laying position as illustrated in Figure 3, and this increase in covering capacity of 90 the elements in a given course, over the actual area of the elements in the course, amounts per element to the same area as that already described as saved during the cutting, that is about $2\frac{1}{2}$ square inches. 95
- Still another advantage of my roofing element resides in the relative tightness of the joints between the adjacent shingles in a course. Proportioned and laid as indicated in Figure 3, leakage thru the joints is effectively prevented. Such insignificant quantity of water as may be driven by high wind thru the joint at the top of the slot 67 goes no farther than the recess 68, and readily finds its way out again without leaking thru the underlying course. 100
- It will of course be understood that while the roofing element or shingle which I have herein described, has a plurality of exposed shingle-tabs separated by slots, it is not confined solely to such multiple-tab form of element. Roofing elements comprising a single exposed tab to each element may advantageously be made by my method. 105
- The term "unlike," used in the claims to 110 define the transverse edges, is meant to include the condition in which lines defining the transverse edges are unlike and cannot be superimposed upon each other.
- I claim:
1. A roofing element comprising a strip of material having each transverse edge defined by a broken line in reverse symmetry about a point between the longitudinal edges, said transverse edges being unlike. 115
  2. A roofing element comprising a strip of material having each transverse edge defined by a broken line in reverse symmetry 120

about a point between the longitudinal edges, said transverse edges being unlike but complementary in part.

3. A roofing element comprising a strip of material having each transverse edge defined by a broken line in reverse symmetry about a point on that edge, said transverse edges being unlike but in part complementary whereby one transverse edge of one element is adapted to interlock with the opposite transverse edge of the adjoining element when laid.

4. A roofing element adapted to be laid with other like elements in overlapping courses, and having each transverse edge defined by a broken line such that in laying position the homologous transverse edges of two adjacent elements are identical and the non-homologous transverse edges may be interlocked, the transverse edges of each element being unlike.

5. A roofing element adapted to be laid with other like elements in overlapping courses, and having on one transverse edge a projection and on the opposite transverse edge having a narrow projection adapted to engage the said first mentioned projection of the adjoining element in the course and having a wide projection adapted to abut against the edge of the said adjoining element to space the two elements in the course.

6. A roofing element adapted to be laid with other like elements in overlapping courses, and having on one transverse edge a projection and on the opposite transverse edge having a wide projection adapted to abut against the edge of the adjoining element in the course to space it from the adjoining element whereby a slot is formed therebetween, and a narrow projection spaced from the wide projection and adapted to engage said first mentioned projection of said adjoining element and therewith close the inner end of said slot.

45 7. A roofing element adapted to be laid with other like elements in overlapping courses, and having on one transverse edge

a projection and on the opposite transverse edge having a wide projection adapted to abut against the edge of the adjoining element in the course to space it from the adjoining element whereby a slot is formed therebetween, and a narrow projection spaced from the wide projection on the same edge and adapted to interlock with said first mentioned projection of said adjoining element and therewith close the inner end of said slot.

8. A roofing element adapted to be laid with other like elements in overlapping courses, and having on one transverse edge a projection and on the opposite transverse edge having a wide projection adapted to abut against the edge of the adjoining element in the course to space it from the adjoining element whereby a slot is formed therebetween, and a narrow projection spaced from the wide projection and adapted to engage said first mentioned projection of said adjoining element and therewith close the inner end of said slot, said element having a plurality of slots in its exposed edge similar to the slot formed between adjacent elements.

9. A roofing element comprising a strip of material having each transverse edge defined by a broken line in reverse symmetry about a point on that edge, said transverse edges being unlike but in part complementary whereby one transverse edge of one element is adapted to interlock with the opposite transverse edge of the adjoining element when laid, and whereby a slot is formed between the adjoining elements.

10. A roofing element comprising a strip of material having each transverse edge defined by a broken line in reverse symmetry about a point between the longitudinal edges, said transverse edges being unlike, and one longitudinal edge being longer than the other longitudinal edge.

In testimony whereof, I have hereunto set by hand.

DOZIER FINLEY.
